UNITED STATES PATENT OFFICE.

HARRY F. ROACH, OF ST. LOUIS, MISSOURI.

RAIL-JOINT.

1,361,774.

Specification of Letters Patent.

Patented Dec. 7, 1920.

Application filed March 6, 1920. Serial No. 363,899.

To all whom it may concern:

Be it known that I, HARRY F. ROACH, a citizen of the United States, residing at St. Louis, Missouri, have invented a certain new and useful Improvement in Rail-Joints, of which the following is a full, clear, and exact description, such as will enable others skilled in the art to which it appertains to make and use the same.

10 This invention relates to rail joints of the type in which two members or bars that are arranged at opposite sides of the webs of the abutting rails are provided with portions which are wedged between the heads 15 and the base flanges of the rails.

The joint members or splice bars of the above-mentioned type that are now in general use are provided at their upper and lower edges with inclined rail engaging surfaces that merge into convexed surfaces which are tangential to said rail engaging surfaces. When such a joint member is first installed the inclined rail engaging surfaces thereon bear snugly against the undersides 25 of the heads and against the upper sides of the base flanges of the rails, the convexed surfaces on said member are positioned opposite to and some distance away from the fillets of the rails and the inner side of said member is spaced some distance away from the webs of the rails, namely, the vertical portions of the rails lying between the inner terminals of the rail fillets, the distance between the inner sides of the joint member and the webs of the rails being generally referred to as the "draw" of the joint members. After the rails or the inclined rail engaging surfaces on the joint members have become worn the bolts of the joint are tightened so as to 30

40 draw or move the joint members inwardly toward the rails sufficiently to compensate for the wear on the coöperating surfaces of said members and rails. It is possible to maintain the desired snug engagement or wedging action between the joint members and the rails for some time after said members have been installed, but after the coöperating inclined surfaces on the rails and the joint members have become worn to such an 45 extent that the convexed surfaces on the joint members engage the fillets of the rails, it is impossible to maintain the joint members in sufficiently snug engagement with the rails to prevent the rails from pounding on 50 said joint members when a load passes over the rail joint. In other words, when the

joint members are new and the "draw" is greatest, it is possible to maintain the contiguous ends of the rails in the same respective planes as to line and surface but after 55 the joint members have become worn, the "draw" becomes less until finally the joint members contact with the webs of the rails and the "draw" is zero, at which point it is necessary to remove the joint members and 60 substitute new or unworn members in place of same. This defect or objectionable characteristic of the ordinary rail joint member or splice bar is well recognized and it has been estimated that the ordinary angle bar 65 or joint member now in general use functions properly or exerts the proper wedging action on the rails for only approximately 46% of the life of said joint member. During the remainder of the life of the joint 70 member its efficiency is materially reduced by reason of the convexed surfaces on the same bearing against the fillets of the rails and thus preventing the inclined surfaces 75 on the upper and lower edges of said member from being held in snug engagement 80 with the heads and the base flanges of the rails.

It has been attempted to remedy the above-mentioned defect of the ordinary rail joint 85 member or splice bar by forming grooves or recesses in the same intermediate the inner side face of said member and the inclined surfaces thereon that bear against the heads and the base flanges of the rails so as to 90 eliminate portions on said member which contact with the fillets of the rails before said member has moved inwardly toward the rails its maximum distance. In theory, a joint member or bar of the character just referred to, namely, a member provided with 95 grooves or recesses located opposite the fillets of the rails, overcomes the defect or objectionable characteristic previously mentioned of the ordinary rail joint member or splice 100 bar, but in practice such a joint member has no practical value, and is as inefficient as a joint member provided with convexed surfaces located opposite the fillets of the rails. This is due to two causes, first, it cannot be 105 made commercially, owing to the fact that it necessitates the use of rolls provided with beads of such diminutive size that they soon break down, thus making the cost of manufacture prohibitive, and second, when such 110 a joint member is in service, the material in the inclined rail engaging portions of the

same flow into the recesses or depressions in said member on account of the fact that there are no portions on said member to resist the lateral component forces produced by the pressure on the inclined rail engaging surfaces on said member. The distortion or flowing of the material into the grooved portions of the joint member form projections thereon that bear against the fillets of the rails and obstruct the inward movement or "draw" of the member toward the rails in the same manner as the convexed surfaces on the ordinary angle bar or joint member now in universal use. In fact, a recessed or grooved joint member is apt to be less efficient than a joint member provided with convexed surfaces disposed opposite the fillets of the rails, on account of the tendency of the material in a grooved or recessed member to flow and form projections thereon soon after the member has been installed. Accordingly the grooved rail joint member or bar that was devised to remedy the defect above mentioned of the ordinary joint member or angle bar has never gone into commercial use, as it is of such design that it cannot be made commercially and will not stand up in service.

The object of my invention is to provide a rail joint member or bar that can be held in sufficiently snug engagement with the heads and base flanges of the rails throughout the major portion of the life of said member to prevent the rails from pounding and which is of such design that it has the following essential characteristics necessary for a successful rail joint member.

First: It can be rolled easily and at no greater cost than an ordinary rail joint member or angle bar; and

Second: The material in the inclined rail engaging portions or surfaces of the same will not flow sufficiently when the joint member is in service to form projections thereon that interfere with the inward movement or "draw" of said member toward the rails.

I have herein illustrated my invention embodied in a Roach rail joint of the general type described in my prior U. S. Patent No. 1,258,249, dated March 5, 1918, but I wish it to be understood that my present invention is applicable to any type of rail joint member or bar that bears against the heads and base flanges of the rails and which is adapted to be moved horizontally toward the webs of the rails to take up wear on the coöperating surfaces on the joint member and on the rails.

Figure 1 of the drawings is a side elevational view, partly broken away, of a rail joint embodying my invention.

Fig. 2 is an enlarged vertical sectional view, illustrating the preferred form of my invention; and

Figs. 3 and 4 are vertical sectional views, 65 illustrating other forms of my invention.

Referring to the drawings, A designates two abutting T rails and B designates two joint members that are arranged on opposite sides of the webs of said rails and retained in position by means of bolts that pass transversely through said members and through the webs of the rails. Each of the joint members B is provided at its upper edge and at a point intermediate its ends, with an inclined rail engaging surface 2 that bears against the undersides of the heads of the rails and at its lower edge with an oppositely inclined rail engaging surface that bears against the upper sides 80 of the base flanges of the rails, as clearly described in my prior U. S. Patent above referred to. It is immaterial, however, so far as my present invention is concerned, whether the rail engaging portions 2 and 85 3 on the joint member extend for only a portion of the length of said member or throughout the entire length of said member.

Instead of providing the member B with 90 a convexed surface at the upper edge of the same that is tangential to and merges into the inclined surface on said member that bears against the heads of the rails, as is now the universal practice in rail joint 95 members of the type that are wedged between the heads and the base flanges of the rails, I form my improved joint member B in such a manner that there is no portion on the same in proximity to the inclined 100 rail engaging surface 2 that will act as an obstruction to prevent said member from being drawn inwardly toward the rails sufficiently to maintain the required snug engagement between said member and the 105 heads and the base flanges of the rails throughout the major portion of the life of said member, or, in other words, until the inner side of said member bears against the webs of the rails. I also make the member 110 B of such form or contour that it can be rolled easily and provide it with a portion that resists the lateral component forces produced by pressure on the inclined rail engaging surface 2 which tend to cause the 115 metal in said surfaces to flow inwardly toward the rails.

In the preferred form of my invention, as shown in Fig. 2, the member B is provided with flat surfaces 4 that are located 120 between the inner side 5 of said member and the inclined rail engaging surfaces 2 and 3 on said member that bear against the undersides of the heads and the upper sides of the base flanges of the rails. When the 125 member B is in operative position the flat surfaces 4 thereon will be disposed opposite the fillets 6 of the rails, thus providing suf-

ficient clearance between the member B and the fillets of the rails to permit said member to move inwardly toward the rails its maximum distance without liability of any 5 portions on said member contacting with or bearing against the rail fillets and thus obstructing the inward movement or "draw" of said member B toward the rails. A rail joint member of the construction 10 above described can be rolled easily and at no greater expense than an ordinary rolled angle bar, owing to the fact that it is of massive design and has no surfaces that necessitate the use of rolls equipped with 15 beads. Another desirable feature of the member B which is an essential requisite of a practicable rail joint member, is that the material in the rail engaging portions, 2 and 3 on same will not flow sufficiently 20 when said member is in service to thus form projections in proximity to the rail engaging surfaces 2 and 3 that interfere with or obstruct the inward movement of the member B toward the rails. I obtain the desirable 25 characteristics just referred to by providing the member B with portions arranged in front of the rail engaging surfaces 2 and 3 that resist the lateral component forces inwardly toward the rails, 30 produced by the pressure that is exerted on the rail engaging surfaces 2 and 3 when a load passes over the joint. In Fig. 2 I have used dotted lines x to indicate the extreme inner ends of the rail engaging surfaces 2 35 and 3 and to show the direction of the resultant effect of the load on the surfaces 2 and 3 when a wheel passes over the joint. By referring to said figure it will be noted that the portions of the member B on which 40 the flat surfaces 4 are formed are located in front of the dotted lines x , or, in other words, between the extreme inner ends of the rail engaging surfaces 2 and 3 and the inner side 5 of the member B. Consequently, 45 the portions 4 of the member B resist the lateral component forces which tend to cause the material in the rail engaging portions 2 and 3 to flow inwardly toward the rails.

50 While I prefer to provide the member B with portions having flat faces 4 which are disposed at an angle to the rail engaging surfaces 2 and 3, it is not absolutely essential that the portions of the member B which 55 resist the lateral component forces on the rail engaging surfaces have flat faces, so long as the planes of the surfaces of said portions intersect the planes of the rail engaging surfaces 2 and 3. In other words, 60 in my improved joint member the portions of the same which are disposed opposite the fillets of the rails are not tangential to the rail engaging surfaces 2 and 3, whereas, in the ordinary joint member or bar the convexed portions of the same which are dis-

posed opposite the fillets of the rails are tangential to and merge into the inclined rail engaging surfaces at the upper and lower edge of the joint member. Accordingly, my joint member is distinguished from the ordinary joint member now in general use in 70 that the plane of the portion of the same opposite the upper rail fillets, intersects the plane of the upper rail engaging surface on said member, instead of merging into the same. In the embodiment of my invention herein illustrated the upper and lower edge portions of the bar are symmetrical, but this is immaterial, so far as my invention is concerned, as my broad idea contemplates 75 providing one or both edge portions of the joint member with surfaces opposite the fillets of the rails, the planes of which intersect the planes of the rail engaging surfaces at the upper and lower edges of said member. In Fig. 3 I have shown another form 80 of my invention, wherein the portions of the member B that prevent the material in the rail engaging portions 2 and 3 from flowing may be provided with convexed surfaces 4^a 85 which are of such contour or curvature and so disposed with relation to the rail fillets that they will not contact with said fillets until the member B has nearly reached its maximum distance inwardly toward the 90 rails.

Nor is it essential that the member B be provided with relatively large masses of material arranged in front of the rail engaging portions at the upper and lower 95 edges of said member, so long as sufficient material is provided to resist the lateral component forces on the rail engaging portions 2 and 3 which tend to cause the material in said portions to flow inwardly toward the rails. Therefore, in Fig. 4 of the drawings I have shown a rail joint member 100 constructed in accordance with my invention whose inner side 5^a is convexed throughout the major portion of its height or 105 throughout its entire height, and whose plane intersects the planes of the rail engaging surfaces 2 and 3, the portions of the inner side 5^a of said member which are disposed opposite the fillets of the rails being 110 so shaped and arranged that they will not contact with the rail fillets at any point in the life of the member B, and thus interfere with said member being drawn inwardly sufficiently to cause the surfaces 2 and 115 3 thereon to bear snugly against the heads and the base flanges of the rails and hold the rails rigidly enough to prevent them from pounding on the joint members when a load 120 passes over the joint. In the form of my invention shown in Fig. 4 the distance between the fillets of the rails and the surfaces 4^b on the member B is great enough so that said surfaces 4^b will not engage the rail fillets 125 until the inner side of the member B bears 130

against the webs of the rails, thus producing a rail joint member that is 100% efficient, or, in other words, efficient throughout its entire life. This is accomplished by 5 slightly reducing the width or bearing area of the rail engaging surfaces 2 and 3 so that the planes of the surfaces 4^b which intersect the planes of the rail engaging surfaces 2 and 3 will start at points slightly farther 10 from the fillets of the rails than the starting points of the surfaces 4 and 4^a on the members B shown in Figs. 2 and 3.

A rail joint member or bar of the construction above described is efficient throughout 15 the major portion of its life or throughout its entire life depending on the starting point of the portions of the same whose plane or planes intersect the planes of the oppositely inclined rail engaging surfaces 2 and 3 because said portions are of such design 20 that the rail engaging surfaces 3 and 4 can be held in sufficiently snug engagement with the rails to prevent the rails from pounding on the members of the joint when 25 a load passes over the joint; it can be rolled easily and at no greater cost than an ordinary angle bar or joint member, and it is of such design that the material in the rail engaging portions of the same will not flow 30 sufficiently to form projections that interfere with the draw of the member.

Having thus described my invention, what I claim as new and desire to secure by Letters Patent, is:

35 1. A rail joint member or bar provided at its upper edge with an inclined rail engaging surface, and a portion on said member that resists the lateral component forces produced by pressure on said rail engaging 40 surface and which is so disposed with relation to the fillets of the rails that it will not obstruct or interfere with the movement of said member inwardly toward the rails during the major portion of the life of said 45 member.

50 2. A rail joint member or bar adapted to be wedged between the heads and base flanges of two abutting rails and being of such cross sectional shape that no portion 55 of the same will contact with the fillets of the rails and thus obstruct the inward movement of said member during all or the major portion of the life of the same, said member having sufficient material in front of the rail engaging portions of the same to resist the lateral component forces which tend to cause the material in said rail engaging portions to flow toward the rails.

60 3. A rail joint member or bar provided at its upper edge with an inclined surface that is adapted to bear snugly against the heads of the rails, and a portion on said member that resists the lateral component forces produced by the pressure on said rail engaging 65 surface and which is of such shape and loca-

tion that said member can move inwardly toward the rails its maximum distance without being interrupted by the upper fillets of the rails.

4. A rail joint member or bar provided at 70 its upper edge with an inclined rail engaging surface that is adapted to snugly engage the heads of the rails, and a portion on said member that resists the lateral component forces produced by pressure on said inclined 75 rail engaging surface and provided with a flat face that lies between said rail engaging surface and the inner side of said member.

5. A rolled rail joint member or bar having 80 its inner side disposed opposite the webs of the rails, oppositely inclined rail engaging surfaces on the upper and lower edges of said member, and portions on said member intermediate the inner side of the same and said inclined rail engaging surfaces that 85 resist the lateral component forces produced by the pressure which a passing load imposes on said rail engaging surfaces and which are so disposed with relation to the fillets of the rails that they will not obstruct 90 or interfere with the movement of said member inwardly toward the rails during the major portion of the life of said member.

6. A rolled rail joint member provided 95 with an inclined surface that is adapted to bear against the underside of the heads of the rails, and a portion on said member disposed opposite the upper fillets of the rails, the plane of said portions intersecting the plane of said inclined rail engaging surface. 100

7. A rail joint member of such cross sectional shape that it will be wedged between the heads and the base flanges of the rails when it is arranged in operative position, said member having a portion opposite the 105 upper fillets of the rails whose plane intersects the plane of the upper rail engaging surface of said member and which is of such form and arrangement that it will not interfere with the "draw" of said member 110 throughout the entire life of said member.

8. A rail joint member or bar provided at 115 its lower edge with an inclined rail engaging surface that is adapted to snugly engage the base flanges of the rails, and a portion on said member that resists the lateral component forces produced by pressure on said inclined rail engaging surfaces and provided with a flat face that lies between said rail engaging surface and the inner side of said 120 member.

9. A rolled rail joint member provided with an inclined surface that is adapted to bear against the top side of the base flanges of the rails, and a portion on said member disposed opposite the lower fillets of the rails and disposed in a plane that intersects the plane of the said inclined rail engaging surface. 125
